UNITED STATES PATENT OFFICE.

PERRY ARNOLD, OF TIPTON, INDIANA.

RAILWAY CAR DOOR.

Application filed November 12, 1920. Serial No. 423,677.

To all whom it may concern:

Be it known that I, PERRY ARNOLD, a citizen of the United States, and a resident of Tipton, county of Tipton, and State of Indiana, have invented a certain new and useful Railway Car Door; and I do hereby declare that the following is a full, clear, and exact description thereof, reference being had to the accompanying drawings, in which like numerals refer to like parts.

This invention relates to car doors, and in particular to railway car doors.

The chief object of this invention is to provide a railway car or the like with a sectionalized door, such that the loading and unloading of said car will be facilitated by use of said door.

The chief feature of the invention consists in sectionalizing the door and providing the several sections with suitable supporting means, whereby the same may be moved from the door closing position into a non-closing position and whereby said door may be locked in either of said positions, or may be secured in an intermediate position.

Other features of the invention relate to the details thereof.

The full nature of the invention will be understood from the accompanying drawings and the following description and claims.

In the drawings, Fig. 1 is a transverse sectional view of a railway car to which the invention has been applied, the door being illustrated in two positions. Fig. 2 is a side elevational view of a railway car showing the parts in the door closing position and being locked or secured therein. Fig. 3 is a sectional view of the locking means taken on line 3—3 of Fig. 2 and in the direction of the arrows the dotted lines showing the door secured in the open position. Fig. 4 is a sectional view of the track support taken on line 4—4 of Fig. 1 and in the direction of the arrows. Fig. 5 is a sectional view of the door construction showing one of said sections in the door closing position, said sectional view being taken on line 5—5 of Fig. 1.

In the drawings there is illustrated the usual box or railway car, the roof of which is supported by suitable beams 20 and the sides thereof being provided with the usual door openings 12, said door openings be-

ing formed of the side posts 13, which posts, as shown clearly in Fig. 5, are substantially L-shaped in cross section, and to the same are secured a T-shaped track 14. Said track is secured to the post such that the head of the T bears against one of the interior faces of the L-shaped post, so that the body of the T or bearing portion 15 thereof forms a channel between itself and the door post 13. As shown clearly in Fig. 1, the door is composed of a plurality of sections 16, several of the sections being hinged together by suitable hinge means 17. To the outer face of each door section, there is secured at each end thereof a spring plate 18, each spring plate is bent and extends angularly from said section and then extends parallel thereto. Upon the parallel portion of said angular extension is suitably supported a roller 19, which roller, as shown clearly in Fig. 5, is rollable between said door plate 18 and the door post 13. With this construction, it will be understood that pressure from the contents within the car will bear against the sections 16 and force said sections to bear against the bearing plate portion 15, thereby forming a tight joint between the door post and said sections.

As shown clearly in Fig. 1, the trackway 14 at each side of the door extends upwardly from the same and is curved inwardly from said door and then extends substantially parallel to the car floor and at right angles to the door closing position. In Fig. 1 the usual opposite doors of the car are each provided with a pair of bent trackways, and as shown in said figure, the overhead portion of one of said trackways is positioned above the overhead portion of the other of said trackways. Thus, both door openings are provided with door means for closing the same.

While the door closing portion of the trackway 13 is secured to the door post, the overhead portion of said trackway is supported from the roof of the car. Associated therewith is a yielding shock absorber construction which is illustrated in detail in Figs. 1 and 4, in which 20 indicates a pair of beams, one of which supports depending and angularly extending brackets or braces 21. Each bracket or brace extends towards a strap or hanger 22 secured to the adjacent beam. The strap 110

2

or hanger 22 suitably supports a strap or plate member 23, which plate member supports a bolt 24, said bolt extending through the free end of the angularly extending brace 21. Positioned upon said bolt member and upon each side of the brace 21 is a coiled spring 25 concentric with said bolt member and secured thereon by means of the washer and nut 26 and 27, whereby the tension of said spring members may be suitably adjusted. One end of each of the springs 25 abuts the brace 21 and the other ends of the springs abut the plate 23 and washer 26 respectively. The four supporting straps or plates 23 carry the four T-shaped trackways 14 in two pairs and in superposed relation by means of suitable bolt members 28. The hereinbefore described construction provides that twisting or weaving of the car or undue vibration thereof will not be transmitted to the trackways in a sufficient amount to permanently deform or damage the same.

It will, of course, be understood that there is sufficient overhead trackway to receive and support all of the door sections when it is desired to have the door opening entirely clear. There is, therefore, provided at each end of the trackway a suitable stop member, such as the bolt 29, for limiting the movement of the door sections in this position. The means for locking the door sections in the overhead position consists in a hinged hasp member 30 secured at one end to the door frame and provided in its end with a staple receiving opening 31. The lowermost door section, when in the door closing position, is provided with a suitable loop or ring member 32 hingedly supported at 33 in a recess 34. The ring 32 is adapted to be associated with the hinged hasp 30 such that a portion of said ring extends through the opening 31 when the lowermost door section is in the elevated position, as shown by the dotted lines in Fig. 3 and is secured in said extending position by means of a snap hook 35 secured to the door opening by suitable means, such as the link chain 36 which is shown in Fig. 2 as associated with the topmost door section to lock the door in closed position. Thus, the doors of the car may be readily secured in the overhead position and in the door opening position such that the workmen may readily disengage said snap hook from the staple ring so as to release the hasp therefrom and permit said door section to be lowered into the door closing position.

The means for locking the door sections in the door closing position when all of said sections are in said position, consists in suitable means, such as the ring 132 which is provided in the outer face of the upper door section. The hinged hasp member 30, when associated with the upper door

section, may be secured thereto by means of a suitable lock 37, or by means of the usual car seal 38.

As shown clearly in Fig. 5, additional locking means is provided, if desired, and this locking means consists of a catch member 40 suitably secured to the door post 13, see Fig. 5, said catch member being adapted to receive the finger operated latching bolt 41, said bolt being provided with a finger piece 42, and said bolt being slidably supported near one end of and upon a door section 16.

If desired, it will, of course, be understood that a plurality of the before mentioned locking means may be provided, both upon the door posts and upon the door sections. Furthermore, said sections may be separated rather than hinged together, or all may be hinged together. When said sections are separated, or at least a portion thereof are separated, then the same are provided with a plurality of bolt latches and said door frames are provided with a plurality of bolt catches, said sections may be secured across the door opening in spaced relation so as to provide ventilation through the door opening such that the car may be used for animals, or for the preservation of material which requires considerable ventilation to prevent spoilage or damage.

The invention claimed is:

1. In a railway car, the combination with a roof, a pair of supporting sides, each provided with an opposite door opening, of a pair of trackways each associated with a door opening, said trackways extending parallel to the sides of said door opening and inwardly above said door opening in substantially parallel relation with said car roof, means for supporting the parallel inwardly extending trackways of both door openings in superposed relation, and a spring construction for yieldingly engaging the trackway supporting means to prevent relative movement of the trackways in the weaving, twisting and vibrating movement of the car, said means comprising a spring construction.

2. In a railway car, the combination with a roof, a pair of supporting sides, each provided with an opposite door opening, of a pair of trackways each associated with a door opening, said trackways extending parallel to the sides of said door opening and inwardly above said door opening in substantially parallel relation with said car roof, and a common means for supporting the parallel inwardly extending trackways of both door openings in superposed relation to prevent relative movement of the trackways in the weaving, twisting and vibrating movement of the car, said means comprising a spring construction.

3. A track support, including a supporting plate, a pair of trackways supported

upon said plate in spaced and superposed relation with each other, means positioned between said trackways for yieldingly engaging said plate to restrain it from lateral 5 movement, and other means associated with said plate for supporting the same.

4. A track support, including a supporting member, a plate suitably supported from said supporting member, a pair of trackways 10 suitably secured to said plate in spaced and superposed relation, a bracket member secured to said supporting member and extending into position adjacent said plate

member, bolt means associated with said plate member and extending through said 15 bracket member, yielding means interposed between said bracket member and said plate member, means adjustably positioned upon the end of said bolt member, and yielding means between said bolt end and said bracket 20 member, said means upon the end of said bolt member being adjustable thereon for adjusting the tension of said yielding means.

In witness whereof, I have hereunto affixed my signature.

PERRY ARNOLD.
